UNITED STATES PATENT OFFICE

ALBERT EUSTACE SHORT AND HUGH OSWALD SHORT, OF ROCHESTER, ENGLAND

MOORING BUOY

Application filed February 12, 1931, Serial No. 515,331, and in Great Britain November 11, 1930.

This invention relates to mooring buoys which are specially applicable for mooring in a river or harbour for use with marine aircraft, yachts, and launches (hereinafter termed "aircraft").

6 The mooring buoys of ordinary iron or steel construction frequently cause damage to the hulls of vessels during mooring operations, owing to their considerable weight and inertia and also to their unyielding character; and damage by impact between the aircraft being moored and such heavy and unyielding buoys frequently takes place during difficult conditions of wind and tide. In 10 using such iron and steel buoys for the mooring of marine aircraft, risk of damage is increased owing to the difficulty of manoeuvring when approaching moorings under unfavourable circumstances, and it will be 15 readily appreciated that owing to the comparatively frail structure of marine aircraft, even a slight impact may cause severe and costly damage to their hulls. Attempts have been made to minimize damage caused 20 by heavy iron and steel buoys, by the application of protective cushions of cork and similar material, but although these cushions afford some local relief, the inertia of the buoy, owing to its heavy weight, imposes 25 stresses on the fabric of the hull which may cause severe damage. In addition to all these disadvantages, corrosion and wear necessitated frequent attention and repair in buoys 30 made of iron and steel.

25 The object of the present invention is to construct mooring buoys of a light and flexible material which will present an elastic face to any craft which comes into contact with it, and which being of light construction will not possess the detrimental inertia inherent in the ordinary iron and steel construction of buoys. Moreover, the buoy constructed in accordance with this invention is 35 practically immune against corrosion.

30 A further object of the invention is to provide this elastic and light construction buoy with suitable anchoring attachment for connection to the mooring cable or chain, and also to provide a light auxiliary system permitting of the aircraft connecting to the

auxiliary system and guiding its final travel until the main mooring chain or cable may be reached or attached.

According to the present invention, the mooring buoy is constructed of light weight 55 pliable material, such, for instance, as waterproof fabric, and which is capable of holding air under light pressure. This buoy is provided with a net, skirt or other stress-distributing means leading from the structure of the buoy itself to a point of attachment to the cable or mooring chain. This point of attachment may comprise a shackle, to which also is coupled one end of a long 60 mooring line provided with eyes or loops at 65 intervals in its length and fitted with a number of small floats or air bags adapted to prevent the mooring line from sinking. The float is preferably of spherical form and may be constructed of an outer casing of canvas 70 containing an inflatable rubber bag, or a plurality of such bags may be employed in order to guard against danger of the buoy sinking owing to accidental puncture. A 75 small amount of buoyant substance, such as expanded rubber or cork, may also be incorporated in the bag or bags, to enable the buoy to continue to float in the event of accidental puncture.

The invention will now be described with 80 reference to some practical embodiments illustrated on the accompanying drawings in which:—

Figure 1 is an elevation of one embodiment of the buoy and the mooring system to be 85 employed therewith.

Figure 2 is a fragmentary view of the buoy illustrating the stopper for the body part of the buoy and the means whereby said body part may be inflated. 90

Figure 3 is a plan view of the upper part of the stopper shown in Figure 2 removed.

Figure 4 is a plan view of the lower part of the stopper shown in Figure 2 removed.

Figure 5 is a fragmentary sectional view 95 of the body of the buoy illustrating the construction of the skirt carrying an attachment for the mooring cable.

Figure 6 is a side elevation of the attachment for the mooring cable. 100

Figure 7 is a section on the line 7-7 in Figure 6.

Figure 8 is a sectional elevation illustrating a further embodiment.

5 Figure 9 is an enlarged fragmentary sectional view illustrating the stopper used in the body illustrated in Figure 8.

In the form of construction shown in Figures 1-7, the buoy comprises a body part 10 formed as a single casing composed of superposed layers of fabric and rubber which are moulded to the required form and vulcanized. This body part marked A in the accompanying drawings is of spherical shape. This 15 form of body part lends itself particularly to the attachment of a depending skirt B which is also composed of superposed layers of fabric and rubber folded over a ring of wire B¹, moulded to the required form and 20 vulcanized. The depending skirt is fitted with eyelets B² to receive the ends C¹ of rods C connecting the skirt with a ring D forming part of an attachment D¹. The ring D is provided with a series of holes D² to receive 25 the ends C² of the rods C.

As shown in Figures 1-4, the buoy is provided with an orifice formed by the outwardly extending part A¹ of the body, which 30 outwardly extending part is held to the required shape by a helically wound embracing wire A² and is fitted with a sealing stopper E. This sealing stopper comprises an upper part E¹ having an orifice E² which is 35 adapted to be opened completely for the initial inflation of the buoy by a bellows, and to be closed by a plug E³ when inflated, and having a non-return valve E⁴ adapted for the attachment of an air pump for adding additional air to increase the inflation to the desired pressure. This upper part E¹ is also 40 provided with a central screwed shank E⁵ and a nut E⁶. The sealing stopper also comprises a lower part E⁷ having a diametrically located web E⁸ formed with a central hole E⁹ 45 for the passage of the shank E⁵. The upper and lower parts of the sealing stopper are externally shaped to correspond with the interior of the extending part A¹ and are securely retained in the extension A¹ by a water tight closure cap E¹⁰ bearing at its periphery E¹¹ in a circular seat E¹² in the lower part of the sealing stopper and having a central hole E¹³ engaging on the shank E⁵ and being engaged by the nut E⁶ to draw and 50 hold the parts of the sealing stopper together.

The orifice formed by the extending part A¹ of the body and the sealing stopper is located centrally of the lower part of the body surrounded by the skirt B, thus when 60 the buoy is attached at its mooring, the stopper will be sealed by water and leakage of air through the stopper will be resisted by the pressure of the water.

As shown in Figures 6 and 7, the attachment D¹ for the mooring cable consists of a

bifurcated part to which is attached by means of the bolt D³, a cable attachment device F of the main mooring cable F¹.

Between the bifurcations of the attachment D¹ and pivoted on the bolt D³ is a shackle G 70 on which is turnably mounted a link H and a cable attachment device I. The free end of the link H is turnably connected to one end of a mooring line J made of rubber so that it will not damage aircraft coming into contact with it. This mooring line is provided at intervals with floats J¹. The floats keep the major part of the mooring line floating on the surface of the water. The mooring line is also provided with a series of mooring loops J². 75 At or near the second float from the buoy a stranded wire rope K forming an auxiliary mooring cable is permanently connected to the floating line by means of the device K¹ in order to prevent it sinking. The wire rope K is provided with a looped end K² which is detachably connected to the floating line by the device K³ so that this wire rope K is available for mooring the aircraft, and being held up by the mooring line can be 80 readily picked up. The opposite end of the wire rope K is attached to the cable attachment device I.

The main stranded wire cable F¹ is used in place of the chain cable which is usually employed with mooring buoys and is fitted with the swivel F² so as to permit rotation of the buoy without communicating similar twisting action to the moorings. The main stranded wire cable F¹ is attached by a swivel 85 connection F³ to a block of concrete F⁴ constituting an anchor. The swivels F² and F³ are especially necessary for permitting the cable to turn without being twisted especially with multi-engine aircraft moored at the 90 buoy when difficulty may be experienced in starting one of the engines. If, under these circumstances, the aircraft circles continuously, the absence of suitable provision for permitting the cable to turn without twisting, 95 may shorten the cable to a dangerous extent. quite apart from the damage such twisting may do to the cable. Any suitable swivel may be employed for preventing the chain or cable from taking up a twist.

In the form of construction shown in Figures 8 and 9, instead of the skirt and connecting rods being independently constructed the body L is formed with a prolongation L¹ to which a stopper or end fitting is fixed. The prolongation L¹ is formed with a double thickness of material and is of frusto-conical shape. The stopper comprises an inner member having frusto-conical sides L² and an arcuate portion L³ formed with perforations 100 L⁴ and an outer member L⁵ formed at its upper end with a frusto-conical recess L⁶ to receive the prolongation L¹, at its lower end with bifurcated portions L⁷, and intermediate its ends with a diaphragm L⁸. The diaphragm 105

L^8 is formed with an orifice L^9 and with a non-return valve L^{10} in a similar manner to the stopper described with reference to Figures 1-4 of the accompanying drawings. A water-tight closure cap L^{11} is provided and this closure cap and the inner and outer members of the stopper are fixed together and to the prolongation L^1 by means of a bolt L^{12} . In such a structure the buoy, instead of being spherical in form, is pear-shaped, the strengthening of the fabric at the prolongation enabling any stress between the cable and the buoy to be equally distributed.

15 All the metal attachments to the buoy, such, for instance, as the stopper with its closure cap, the attachment and its shackle and the connecting rods, are made of non-corrodible metal, such, for instance, as stainless steel or 20 gun-metal. The stranded wire cables are also made of non-corrodible metal or otherwise adequately protected from the action of salt water, and phosphor-bronze or stainless steel may suitably be used for this purpose. The 25 cable is also fitted to non-corrodible swivels.

In one construction of the buoy, it may be adapted for use at night. In such a construction, a gutta percha or other flexible non-corrodible container is mounted in the upper 30 part of the buoy and is formed with a lid or cover consisting of a lens. In the container a light is located, which is illuminated by a suitable storage battery, operable by a switch on the exterior of the buoy. A rubber 35 cushion is formed around the outside of the lens to protect it from damage.

What we claim as our invention and desire to secure by Letters Patent is:—

1. A mooring buoy, comprising a hollow, 40 air-tight and flexible body constructed of light-weight, pliable material, said body having a prolongation; and a stopper on said prolongation forming an attachment for a mooring cable.

45 2. A mooring buoy, comprising a hollow, air-tight and flexible body constructed of light-weight, pliable material; a skirt leading from said body; and an attachment for a mooring cable on said skirt.

50 3. A mooring buoy, comprising a hollow, air-tight and flexible body constructed of light-weight, pliable material; a sealing stopper in said body; means in said stopper adapted to open completely for the attachment of bellows for initially inflating said body; a valve for the attachment of an air pump for increasing the inflation to the desired pressure; stress-distributing means leading from said body and an attachment 55 for a mooring cable on said stress-distributing means.

4. A mooring buoy, comprising a hollow, 60 air-tight and flexible body constructed of light-weight, pliable material, said body having a prolongation; a stopper in said pro-

longation forming an attachment for the mooring cable; means in said stopper adapted to open completely for the attachment of bellows for initially inflating said body; and a valve adapted for the attachment of an air pump for increasing the inflation to the desired pressure. 70

5. A mooring buoy, comprising a hollow, air-tight and flexible body constructed of light-weight, pliable material; a sealing stopper in the bottom of said body adapted to be submersed; means in said stopper adapted to open completely for the attachment of bellows for initially inflating said body and to be closed when the body is inflated; a non-return valve adapted for the attachment of an air-pump for increasing the inflation to the desired pressure; stress-distributing means leading from said body; and an attachment for a mooring cable on 80 said stress-distributing means.

6. A mooring buoy, comprising a hollow, air-tight and flexible body constructed of water-proof fabric, said body having a prolongation; and a stopper in said prolongation forming an attachment for a mooring 85 cable.

7. A mooring buoy, comprising a hollow, air-tight and flexible body constructed of light-weight, pliable material; stress-distributing means leading from said body; an attachment for a mooring cable on said stress-distributing means; and an auxiliary mooring device to which aircraft can be connected and by which aircraft can be guided until 90 the mooring cable is reached.

8. A mooring buoy, comprising a hollow, air-tight and flexible body constructed of light-weight, pliable material; stress-distributing means leading from said body; an attachment for a mooring cable on said stress-distributing means; and a mooring line connected to said attachment and adapted to float and having loops at intervals along the 100 length of said mooring line to which aircraft can be connected and by which aircraft can be guided until the mooring cable is reached. 110

9. A mooring buoy, comprising a hollow, air-tight and flexible body constructed of light-weight, pliable material, said body having a prolongation; a stopper on said prolongation forming an attachment for a mooring cable; and a mooring line connected to said attachment and adapted to float and having loops at intervals along the length of 115 said mooring line to which aircraft can be connected and by which aircraft can be guided until the mooring cable is reached.

10. A mooring buoy, comprising a hollow, air-tight and flexible body constructed of light-weight, pliable material; a stress-distributing means leading from said body; an attachment for a mooring cable on said stress-distributing means; a shackle on said at- 120 125 130

tachment; and an auxiliary mooring device connected to said shackle, to which auxiliary mooring device aircraft can be connected and by which aircraft can be guided until the mooring cable is reached.

11. A mooring buoy, comprising a hollow, air-tight and flexible body constructed of light-weight, pliable material; stress-distributing means leading from said body; an attachment for a mooring cable on said stress-distributing means; an auxiliary mooring device to which aircraft can be connected and by which aircraft can be guided until the mooring cable is reached; and an auxiliary mooring cable attached to the auxiliary mooring device and having a loop for the attachment of aircraft thereto.

12. A mooring buoy, comprising a hollow, air-tight and flexible body constructed of light-weight, pliable material; stress-distributing means leading from said body; an attachment for a mooring cable on said stress-distributing means; a shackle on said attachment; an auxiliary mooring device connected to said shackle and adapted to float; and an auxiliary mooring cable attached at one end to said shackle and attached near its opposite end to the auxiliary mooring device and having a loop for the attachment of aircraft thereto.

13. A mooring buoy, comprising a hollow, air-tight and flexible body constructed of light-weight, pliable material; a stress-distributing means leading from said body; an attachment for a mooring cable on said stress-distributing means; a shackle on said attachment; a mooring line connected to said shackle having loops at intervals to which mooring line aircraft can be connected and by which aircraft can be guided until the mooring cable is reached; and an auxiliary mooring cable attached at one end to said shackle and near its opposite end to the mooring line and having a loop to which the aircraft can be attached.

In witness whereof we have hereunto set our hands.

ALBERT EUSTACE SHORT.
HUGH OSWALD SHORT.
